ATTORNEY

UNITED STATES PATENT OFFICE.

GEORGE H. ST. JOHN, OF DETROIT, ASSIGNOR OF ONE-HALF TO WILLIAM W. ANDRUS, OF ATTICA, MICHIGAN.

BAG-FASTENER.

SPECIFICATION forming part of Letters Patent No. 271,536, dated January 30, 1883.

Application filed August 30, 1881. Renewed June 29, 1882. (No model.)

To all whom it may concern:

Be it known that I, GEORGE H. ST. JOHN, of Detroit, county of Wayne, State of Michigan, have invented a new and useful Improvement 5 in Bag-Fasteners; and I declare the following to be a full, clear, and exact description of the same, such as will enable others skilled in the art to which it pertains to make and use it, reference being had to the accompanying 10 drawings, which form a part of this specification.

My invention consists of the combinations of devices and appliances hereinafter set forth and claimed.

15 In the drawings, Figure 1 is a perspective view of a device embodying my invention. Fig. 2 is a longitudinal section of the same, and Fig. 3 a cross-section. Fig. 4 represents a mail-bag with my device in use. Fig. 5 is a 20 perspective view illustrating the method of housing the slack cord, and showing the latter partially wound into the block.

Heretofore it has been customary to employ various kinds of fastening devices; but generally the loose or slack cord, when the bag has been closed, is cumbersome to dispose of, and is tied up into a bow-knot or other shape, so as to be out of the way. Such ends, however, frequently become entangled, and rather 30 than spend the time to untie or disentangle them they are frequently cut and destroyed. With the large number of mail-sacks in daily use this becomes a source of great expense and annoyance. It is the object of my invention 35 to supply a means for taking up and housing this slack cord, and at the same time effectually fasten the bag-mouth.

Referring to the drawings, A represents a mail-sack or other bag of similar character. 40 B is its closing-cord.

C is my improved tying device. It consists of an open block or frame, there being a lower plate, C', which rests upon and is secured by rivets c' or otherwise to the sack, there being 45 a suitable washer of leather or metal at c', within the sack, to form a secure fastening for the rivets.

c' are posts projecting up from the lower plate to support the outer or cap plate, and 50 made hollow for the passage of the rivets attached to the cap-plate.

C² is the cap-plate, and c' are rivets projecting therefrom through the hollow posts c', and riveted to the under side of the plate C', as shown. The plates C' C² are each beveled outwardly at their edges, and are adjusted a little distance apart, so as readily to guide the slack cord into the interior as it is wound up. There are one or two holes, c⁵, at the upper end of the plate C', through which the two strands of 60 the tying-cord are passed. This part of the device will now be understood.

When it is desired to close the mouth of the sack the tying-cord is drawn up tight in the usual way. The long slack end of the cord is 65 then wound round and round between the plates C' C² about the posts c' until it has all or nearly all disappeared within the cavity between the plates. The edges of the lower plate are raised so as to form an upwardly-projecting ridge, and the cap-plate C² is considerably concaved beneath, so that the two will leave ample space between them for the cord as it is wound in, and yet the edges come so near to 70 each other that the cord, once housed, is not liable to come loose or unwind from the block or frame except it is intentionally done. The cord is thus kept in good condition, is not entangled, and is entirely housed and out of the way when the bag is in use, except, perhaps, 75 the extreme end.

If it is desired to affix labels to the bag-fasteners, the outer surface of the outer plate may be provided with a dovetailed recess, one end of which is open, and into which may be 85 slipped and firmly secured at its edges a label or tag, D, of the usual character.

In order that the tag may not be accidentally slipped out of its place, and yet be so arranged as to offer no obstruction to the ready removal 90 of it when desired, I make a small ridge or lip upon the plate outside the end of the dovetailed slot, at d, and over which the tag or label can be readily forced by the thumb of the operator.

I would have it understood that I do not confine myself to the precise form of plates C' C² shown in the drawings, for they may be considerably varied therefrom without departing from my invention. So, also, the plate and 100 cap may be adjusted, if desired, closer together at one end than at the other, so as to freely ad-

mit the cord at one end, but offer a considerable obstacle to its disengagement at the other end.

I would also have it understood that I do not limit myself to the hollow posts c^3 and rivets c^4 , for the posts may be made solid and their upper ends be riveted to the top plate, or, projecting down from the top plate, may be riveted to the bottom plate, if desired.

10 I am aware that a bag-cord holder has been composed of two facing-plates with flat inner surfaces for gripping the tying-cord, and I do not claim such construction.

What I claim is—

15 1. A bag-cord holder composed of two plates facing each other, with their edges separated and their facing surfaces connected by one or more interior posts, one or both of said plates

having the inner surface thereof concave to form a housing for the tying-cord, and the inner plate being adapted for attachment to a bag, substantially as described.

2. The combination, with a bag, of a drawing-cord and the cord-holder composed of the two plates connected by an interior post or 25 posts, the inner plate being provided with the two marginal holes through which the two strands of cord are passed, substantially as described.

In testimony whereof I sign this specification in the presence of two witnesses.

GEORGE HENRY ST. JOHN.
